United States Patent Office

Des. 221,845
Patented Sept. 14, 1971

221,845

TRACTOR CAB

Leo J. Lorenz, Farmington, and Wilford E. Bean, Southfield, Mich., assignors to Massey-Ferguson Inc., Detroit, Mich.

Filed Aug. 21, 1970, Ser. No. 24,620

Term of patent 14 years

Int. Cl. D12—16

U.S. Cl. D14—27

Fig. 1

Fig. 2

Fig. 3

Fig. 4

FIG. 1 is a perspective view of a tractor cab embodying our new design and taken generally from the front and left side thereof;

FIG. 2 is a perspective view of a tractor cab taken generally from the rear and left side thereof;

FIG. 3 is a perspective view of a tractor cab taken from the left side thereof; and

FIG. 4 is a perspective view of a tractor cab taken from the right side thereof.

We claim:

The ornamental design for a tractor cab, substantially as shown.
